(57) **CLAIM**

The ornamental design for a motorcycle undertail exhaust, as shown and described.

DESCRIPTION

FIG. 1 is a rear perspective view of an embodiment of the motorcycle undertail exhaust.

FIG. 2 is a rear elevational view of the motorcycle undertail exhaust; and,

FIG. 3 is a bottom plan view of the motorcycle undertail exhaust.

The broken lines shown in FIGS. 1-3 are included for the purpose of illustrating environmental elements only and form no part of the claimed design.

1 Claim, 2 Drawing Sheets

FIG. 3
